UNITED STATES PATENT OFFICE.

HALBERT POWERS GILLETTE, OF ROCHESTER, NEW YORK, ASSIGNOR TO
JULIA S. GILLETTE, OF ROCHESTER, NEW YORK.

COIN-CONTROLLED APPARATUS.

SPECIFICATION forming part of Letters Patent No. 727,123, dated May 5, 1903.

Application filed December 10, 1901. Serial No. 85,880. (No model.)

To all whom it may concern:

Be it known that I, HALBERT POWERS GILLETTE, a citizen of the United States, residing at Rochester, in the county of Monroe and

5 State of New York, have invented certain new and useful Improvements in Coin-Controlled Apparatus; and I do hereby declare the following to be a full, clear, and exact description of the invention, such as will enable others skilled in the art to which it appertains to make and use the same.

My present invention relates to improvements in coin-controlled apparatus, and more particularly to that class of such devices 15 wherein the insertion of the proper coin into the coin-slot will throw the mechanism into operative position, but the insertion of a counterfeit or slug will cause the same to be ejected without the mechanism being thrown 20 into operation or effected in any manner. In this connection I may also provide mechanism adapted to be brought into action through such slug or the like to give an audible or visual alarm, or, if preferred, both 25 audible and visual alarms may be brought into action.

Through my invention is provided a positive detector which will automatically distinguish the genuine coin from the imitation 30 or slug, the imitation or slug passing through without throwing the parts into operative position.

Other features of novelty and advantage will hereinafter more fully appear, reference 35 being had to the accompanying drawings, wherein—

Figure 1 is a plan view, partly in section, and Fig. 2 is a front elevation, partly in section, of the coin-controlled mechanism.

40 In the views is shown one embodiment of my said invention.

1 represents the crank-shaft, suitably mounted to revolve in the casing 24, inclosing the mechanism. Rigidly mounted upon 45 this shaft 1 is a disk or annular collar 16. In the periphery of this collar 16 is radially set the pin or finger 2, having its pointed end projecting beyond the periphery of said collar. Immediately adjacent said finger 2 50 is a recess long enough to receive an ordi-

nary-sized coin or similar-shaped object. Behind this recess is provided a cam-shaped projection 4, constituting a slug ejector or clearer.

3 is a bell-crank lever pivoted at 5 to some 55 stationary part of the machine, so as to allow the same to swing around in the horizontal plane. 6 is a spring acting upon this lever 3 to normally retain the same against the stop 26. One end of this lever 3 is cut away 60 or slotted in such manner as to constitute a coin-receiver adapted to allow a coin to pass through said slots until the same rests upon the periphery of the collar 16. 11 is a projection carried upon the coin-receiver adapted to come beneath the coin-chute 12 when said receiver is displaced from its normal position, and thereby check the passage of a coin until the coin-receiver resumes its normal position beneath the chute 12. 7 is a spring 70 which, if desired, may be inserted in one of said slots of the receiver in such manner as to retard the passage of an object through the coin-receiver, thereby making the mechanism more positive in its action; but this 75 spring is not essential to the proper operation of the device and may be omitted, if preferred.

9 represents a pivoted lever or dog, having one end resting upon the end of the bell-crank 80 3. This lever or dog is acted upon by the spring 10, which normally tends to press upon the bell-crank 3 in such a manner that when the bell-crank 3 is moved out of its normal position said dog 9 will drop into place be- 85 hind the bell-crank and retain the same in such position until the cam 8 upon the crank-shaft engages said dog to release the same. A stop 25 is provided upon the dog 9 to limit the 90 downward movement of the same.

Mounted beneath the coin-receiver is a V-shaped table having the inclined surface 14 extending in one direction and the inclined surface 15 extending in the opposite direction, at the base of which is formed the coin- 95 box 17.

18 is a tipple pivotally mounted upon the casing or other portion of the machine, one end of which is adapted to be acted upon by gravity from a falling body upon the incline 100

14. The other end of this tipple is adapted to strike against a bell 20 or the like to give an audible alarm. At the same time an electrical contact will be made with said bell, 5 completing an electrical circuit 23 from the source of current-supply 22, thus causing the bell 19 to sound and the lamp 21 to glow.

To operate the mechanism, a good coin of the proper denomination is placed in the coin-chute 12. This coin will fall until it rests in the coin-receiver upon the periphery of the collar 16, where it will remain until the crank-shaft carrying the collar 16 is rotated. When the pin 2 upon the periphery of this collar 16 15 engages the coin, the irregularities in the surface of the coin will prevent slipping of the point of said pin or finger 2. Further rotation of the shaft 1 will cause the coin (indicated by 13) to slide downwardly in the coin-receiver. 20 At the same time the coin-receiver 3 is forced away from the collar 16, causing the coin-receiver 3 to rotate about its spindle 5 until it takes up the position shown in dotted lines in Fig. 1, whereupon the dog 9 catches and 25 restrains the coin-receiver from moving back to its old position under the action of the spring 6. The coin 13 having been dragged downward by the finger 2 is released as the finger begins to recede from the coin-receiver 30 in the course of its revolution, and the coin then drops to the right of the apex of the two tables 14 and 15 and slides down table 15 into the box 17. When the coin-receiver 3 has taken up the position shown in the dotted 35 lines, the gate partially closes the chute 12, so that if another coin were immediately dropped down the chute it would be held back by the gate 11 until the cam 8 has by further revolution of the crank tripped the dog and 40 so permitted the coin-receiver 3 to resume its normal position. Indeed, it is evident that the coin-chute 12 may be filled up with coins one on top of the other; but the gate 11 will permit only one coin at a time to pass down to 45 the coin-receiver, and that one coin having performed its function and not until it has performed its function another coin is released, and only one is released.

It is well known that most counterfeits used 50 to work coin-controlled mechanism are iron washers, lead bullets hammered flat, tin, brass, or other metallic slugs, and these, as I have observed, are almost without exception smooth upon the surface. For convenience 55 I shall term all such counterfeits "slugs." If a slug is dropped down the coin-chute instead of a good coin, the result is entirely different, for the finger 2 upon striking the smooth face of the slug will slip, due mainly 60 to the difference in angles at which the resistive forces offered by the surface of the receiver and the pointed finger act. This slipping is also due to the fact that the smooth surface offers no appreciable resistance to the 65 pointed finger, such as is caused by the raised characters upon a coin. However, to make

the operation certain even where there are slight irregularities in the face of a slug to which the finger would adhere, I have provided the flat spring 7, which resists the downward motion of the slug and so insures slipping of the finger; but the spring is so arranged and adjusted to yield laterally, permitting a good coin to pass down into the coin-box. As a further precaution I prefer 75 to make the portion of the receiver 3 receiving the coin magnetic, to which slugs of iron or the like will be attracted, where they will cling until wiped off by the slug-ejector 4. After the finger 2 has slipped past the lower 80 edge of the slug the slug is wiped down and out by the slug-ejector 4, the notch or recess in the collar being cut out, as shown, so as to permit a slug to fit therein, and as the coin-receiver 3 is not pushed back, as when a good 85 coin is used, the slug necessarily escapes, so as to slide down the incline 14 upon tipple 8, ringing bell 20, closing electric circuit 23, and causing alarms controlled by said circuit, as a bell 19, a lamp 21, or any other suitable device. 90

I do not claim the invention covering the broad idea of using a gate to control a coin-chute; but I am not aware that there has ever before been used a gate controlling a 95 coin-chute which is automatic in its action, opening and closing at definite periods in the cycle of operation of the coin-controlled mechanism, and permitting one and only one coin to descend at a time. 100

I have not shown nor described how the movement of the dog 9 under the action of the spring 10 or how any other movable part of the mechanism may be made to control the delivery of any article to be vended or to 105 control the driving-gear of any mechanism, as that does not constitute a part of my invention, which is universal in its application to all coin-operated machines.

While I have shown a rotatable finger and 110 a rotatable coin-receiver, it is evident that by changes in the mechanism that are not material I may make either the receiver or the finger stationary, all that is essential being motion of the one relatively to the other, and 115 I may substitute reciprocating for rotating parts, and I may entirely omit a dog or locking device.

While I have shown and set forth only one particular form in which my said invention 120 is embodied, many changes and modifications might suggest themselves to any one skilled in the art, and I therefore do not confine myself to the form of device shown, as such changes and modifications might be made in 125 my said invention without departing from the spirit of my invention.

Having thus described my invention, what I claim, and desire to secure by Letters Patent of the United States, is—

1. In coin-controlled mechanism, the combination of a slotted coin-receiver, a rotatable

collar extending into and normally preventing the passage of a coin through said receiver, and means carried by said collar adapted to displace said coin-receiver during the passage 5 of a coin through said receiver.

2. In coin-controlled mechanism, the combination of a slotted coin-receiver, a rotatable collar extending into and normally preventing the passage of a coin through said receiver 10 and a pointed finger carried by said collar adapted to displace said coin-receiver during the passage of a coin through said receiver.

3. In coin-controlled mechanism, the combination of a slotted coin-receiver, a rotatable collar extending into and normally preventing the passage of a coin through said receiver, a finger carried by said collar adapted to displace said coin-receiver during the passage of a coin through said receiver, and a slug-ejector 15 carried by said collar behind said finger.

4. In coin-controlled mechanism, the combination of a movable coin-receiver, a rotatable collar normally preventing the passage of a coin through said receiver, a shaft for rotatably mounting said collar, means carried 20 by said collar for displacing said receiver, and means carried by said shaft for replacing said receiver.

5. In coin-controlled mechanism, the combination of a movable coin-receiver, a rotatable collar normally preventing the passage of a coin through said receiver, a shaft for rotatably mounting said collar, means carried 25 by said collar for displacing said receiver, and a cam carried by said shaft for replacing said receiver.

6. In coin-controlled mechanism, the combination of a movable coin-receiver provided with a slotted cover, a rotatable collar adapted 30 to enter through said slotted cover and normally prevent the passage of a coin through said coin-receiver, and a finger fastened to said rotatable collar and adapted to seize the raised rim or raised characters upon the coin.

45 7. In coin-controlled mechanism, the combination of a movable coin-receiver, a spring projecting into the coin-pathway in the receiver, a movable pointed finger adapted to seize the raised rim or raised characters upon 50 the face of a coin located in said coin-receiver against the resistance of said spring, but in the absence of such raised rim or characters failing by slipping to drag such coin or check past said spring.

55 8. In coin-controlled mechanism, the combination of a movable magnetized coin-receiver, a pointed finger, means for moving said finger relatively thereto, so as to grip a coin in said receiver, and a slug-ejector adapted 60 to remove a slug or the like adhering to said coin-receiver.

9. In coin-controlled mechanism, the combination of a slotted coin-receiver, a rotatable collar extending into and normally closing the 65 said slot, and means carried by said collar for displacing said receiver.

10. In coin-controlled mechanism, the combination of a movable coin-receiver, a rotatable collar adapted to normally prevent the passage of a coin through said receiver, a finger carried by said collar adapted to force a coin through said receiver, and a slug-ejector 70 also carried by said collar.

11. In coin-controlled mechanism, the combination of a movable coin-receiver, a rotatable collar adapted to normally prevent the passage of a coin through said receiver, means carried by said collar for engaging a coin in said receiver to displace the latter, and means for retaining said receiver temporarily in its 80 displaced position.

12. In coin-controlled mechanism, the combination of a movable coin-receiver, a rotatable collar adapted to normally prevent the passage of a coin through said receiver, a 85 pointed finger carried by said collar adapted to engage a coin and displace said receiver, and means for temporarily retaining said receiver in its displaced position.

13. In coin-controlled mechanism, the combination of a movable coin-receiver, a coin-chute above said receiver, a rotatable collar adapted to normally prevent the passage of a coin through said receiver, a pointed finger carried by said collar adapted to engage a 95 coin and displace said receiver, and means carried by said receiver adapted to close said coin-chute during the displacement of said receiver.

14. In coin-controlled mechanism, the combination of a movable coin-receiver, a coin-chute above said receiver, a rotatable collar adapted to normally prevent the passage of a coin through said receiver, a pointed finger carried by said collar adapted to engage a 105 coin and displace said receiver, and a projection carried by said receiver adapted to rest beneath said coin-chute during the displacement of said receiver.

15. In coin-controlled mechanism, the combination of a movable coin-receiver provided with a coin-receptacle, a rotatable collar projecting into said coin-receptacle normally preventing the passage of a coin therethrough, a pointed finger carried by said collar adapted 110 to engage the roughened face of a coin in said receptacle, and a spring carried by said receiver adapted to retard the passage of a coin through said receiver.

16. In coin-controlled mechanism, the combination of a movable coin-receiver provided with a coin-receptacle, a rotatable collar projecting into said coin-receptacle, normally preventing the passage of a coin therethrough, a pointed finger carried by said collar adapted 115 to engage the roughened face of a coin in said receptacle, a spring carried by said receiver adapted to retard the passage of a coin therethrough, a slug-ejector carried by said collar, a recess being provided upon the periphery of said collar between said slug-ejector and finger to receive the coin or slug. 120 125 130

17. In coin-controlled mechanism, the combination of a horizontally-movable coin-receiver, provided with a vertical slot, a rotatable collar extending into said slot, means for displacing said receiver, a partition beneath the slot in said receiver, providing separated compartments, and an alarm or signal device located in one of said compartments.

In testimony whereof I have signed my name to this specification in the presence of ~~to~~ two subscribing witnesses.
